Primary Examiner — Wan Laymon*Assistant Examiner* — Clint A Samuel(74) *Attorney, Agent, or Firm* — Buche & Associates, P.C.; John K. Buche; Bryce A. Johnson(57) **CLAIM**

I claim the ornamental design for "bottle opener," as shown and described.

DESCRIPTION

FIG. 1 is a perspective view of a bottle opener shown in an open position;

FIG. 2 is a front view thereof;

FIG. 3 is a back view thereof;

FIG. 4 is a bottom view thereof;

FIG. 5 is a top view thereof;

FIG. 6 is a right-side view thereof;

FIG. 7 is a left-side view thereof; and,

FIG. 8 is a perspective view shown in a closed position. Broken lines illustrate environmental features and form no part of the claimed design.

1 Claim, 5 Drawing Sheets(56)
